CLAIM

We claim the ornamental design for a beverage container lid, as shown and described.

DESCRIPTION

FIG. 1 is a top, front, right perspective view of a beverage container lid, showing our new design in a condition for use; FIG. 2 is a bottom, rear, right perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; and, FIG. 8 is a bottom plan view thereof.

In the drawings, the equal-length broken lines on the beverage container depict portions of the beverage container lid that form no part of the claimed design. The equal-length broken lines showing a related beverage container depict environmental structure and also form no part of the claimed design.
